Primary Examiner — Michelle E. Wilson*Assistant Examiner* — Rochel L Rimelspach-Zare(74) *Attorney, Agent, or Firm* — Hawaii Patent Services; Nathaniel K. Fedde; Kenton N. Fedde(57) **CLAIM**

The ornamental design for a puzzle board, as shown and described.

DESCRIPTION

FIG. 1 is a front, left, top perspective view of a puzzle board, showing my new design;
FIG. 2 is a rear, right, bottom perspective view thereof;
FIG. 3 is a front elevational view thereof;
FIG. 4 is a rear elevational view thereof;
FIG. 5 is a left side view thereof;
FIG. 6 is a right side view thereof;
FIG. 7 is a top plan view thereof;
FIG. 8 is a bottom plan view thereof;
FIG. 9 is an enlarged view of detail 9 in FIG. 1;
FIG. 10 is an enlarged view of detail 10 in FIG. 1;
FIG. 11 is an enlarged view of detail 11 in FIG. 1;
FIG. 12 is an enlarged view of detail 12 in FIG. 1;
FIG. 13 is an enlarged view of detail 13 in FIG. 2;
FIG. 14 is an enlarged view of detail 14 in FIG. 2;
FIG. 15 is an enlarged view of detail 15 in FIG. 2;
FIG. 16 is an enlarged view of detail 16 in FIG. 2;
FIG. 17 is an enlarged view of detail 17 in FIG. 2;
FIG. 18 is an enlarged view of detail 18 in FIG. 3;
FIG. 19 is an enlarged view of detail 19 in FIG. 3;
FIG. 20 is an enlarged view of detail 20 in FIG. 7;
FIG. 21 is a front, left, top perspective view thereof in an alternate configuration;
FIG. 22 is an enlarged view of detail 22 in FIG. 21; and,
FIG. 23 is an enlarged view of detail 23 in FIG. 21.
The dash-dot-dash broken lines are for notating enlarged views and form no part of the claimed design.
